UNITED STATES PATENT OFFICE.

HAMILTON LINDSAY, OF CLEVELAND, OHIO, ASSIGNOR TO THE LIBERTY REED COMPANY, OF CLEVELAND, OHIO, A CORPORATION OF DELAWARE.

REED FOR WEAVING WIRE CLOTH.

Application filed April 14, 1922. Serial No. 552,774.

To all whom it may concern:

Be it known that I, HAMILTON LINDSAY, a citizen of the United States, residing at Cleveland, in the county of Cuyahoga and State of Ohio, have invented a certain new and useful Improvement in a Reed for Weaving Wire Cloth, of which the following is a full, clear, and exact description, reference being had to the accompanying drawings.

This invention relates to reeds such as are used in looms, for weaving wire cloth, and has for one of its objects the provision of an improved reed construction which tends to lengthen the period of service of a reed.

A construction heretofore employed for making reeds has been to secure the reed teeth, or dents, between binding strips which extend transversely of the teeth and longitudinally of the batten frame. These binding strips are usually made of wood, and are so connected that when the batten strikes the woven fabric to drive a shoot wire into position, the stresses incident to the blow are transmitted directly to these strips. Since the teeth are placed edgewise intermediate these strips, the force of the blow tends to drive the teeth into the wooden strips, thus cutting them and materially shortening the life of the reed.

My invention seeks to overcome this tendency to cut by providing metallic inserts on the batten strips adjacent the edges of the teeth, and at the same time leaving sufficient material above and below the insert for securely holding the teeth in spaced relation to each other after the reed is assembled.

The means for accomplishing my invention will be hereinafter fully set forth in the following description which pertains to the accompanying drawings, and the essential features will be summarized in the claims.

In the drawings, Fig. 1 is a perspective view of a portion of a loom which carries a reed constructed according to my invention; Fig. 2 is a transverse section on an enlarged scale through the batten frame; and Fig. 3 is a perspective view showing the reed construction.

My invention is particularly adapted for use on looms for weaving wire fabric and

accordingly I have shown the frame of such a loom 10, with a batten 11, which is adapted to carry a reed, indicated generally at 12. The reed may be held in position by clamping strips 13 and 14 which are shown as being secured to the batten frame 11, and as extending from one side to the other of the loom frame.

The reed proper comprises teeth or dents 15, which are held in alignment by binding strips 16 extending transversely thereof along the top, and similar strips 17, along the bottom. The dents are held in spaced relation by the usual spacing tape 18 and 19 which is wound around the binding strips, and between adjacent teeth.

The binding strips 16 and 17 are provided on the inner faces thereof with inserts 20 and 21 respectively. These inserts are preferably metallic strips which are embedded in the wooden binders, so that the exposed face thereof lies in the same plane as the faces of the binders which engage the dents of the reed. The arrangement of the binding strips with relation to the reed permits the reversal of the reed within the batten frame, thus doubling the period of service of the reed.

The usual manner of attaching the reed to the batten is illustrated in Fig. 2, wherein the clamping members 13 and 14 engage the binding strips, thus leaving the space intermediate the binders for movement of the warp wires to form a shed. For enabling the binders to be clamped tightly against the batten frame without damage to the reed, suitable metallic inserts 22 and 23 are placed on the exterior of the strips, opposite the inner inserts.

A reed constructed according to my invention is still adapted for use in existing looms and is capable of a longer period of service therein by means of the metallic contact between the inserts and the edges of the dents. Furthermore, these particular inserts may be embedded in existing binding strips without necessitating material changes in the construction thereof, and without impairing the character of the work woven by looms employing this type of reed.

I claim:

1. A reed for a loom comprising in combination, a plurality of dents placed side by

side, a non-metallic binding strip extending transversely thereof, and a metallic insert in said strip adjacent said dents.

2. A reed for a loom comprising in combination, a plurality of dents placed side by side, binding strips extending transversely thereof, and metallic inserts in some of said strips adjacent said dents.

3. In a device of the class described, the combination with a plurality of reed dents, of non-metallic binding strips extending on either side thereof, and metallic inserts embedded in each of said strips, said inserts extending substantially the entire length of the inserts and adjacent said dents.

4. In a device of the class described, the combination with a plurality of reed dents, of wooden binding strips extending on either side thereof, and metallic inserts embedded in each of said strips adjacent the dents, one of the exposed faces of each insert being flush with the adjacent face of the associated strip.

5. In a device of the class described the combination with a plurality of reed dents placed side by side, of means for retaining said dents in spaced relation to each other, and metallic strips adjacent said dents

whereby the working stresses set up in the dents are transmitted to the batten frame 30 through said strips.

6. In combination, a plurality of reed dents placed side by side, a pair of binding strips extending transversely thereof and along the top, another pair of strips extending transversely thereof and along the bottom, and a metallic bearing plate carried by each of said strips and on that portion thereof adjacent said dents.

7. In a device of the class described, the combination with a plurality of reed dents placed side by side, of a pair of non-metallic binders extending along the top of the dents, another pair of binders extending along the bottom of said dents, a metallic insert embedded in each of said binders adjacent the central portion thereof, each of said inserts having a width less than the width of the associated binders, and means for retaining the binders adjacent said dents 50 whereby the faces of the inserts and binders lie substantially in the same plane.

In testimony whereof, I hereunto affix my signature.

HAMILTON LINDSAY.
